[57] CLAIM

The ornamental design for a toilet bowl chlorinator, as shown and described.

DESCRIPTION

FIG. 1 is a side elevation view of a design for a toilet bowl chlorinator;

FIG. 2 is a front elevation view of said toilet bowl chlorinator;

FIG. 3 is a plan view of said toilet bowl chlorinator; and,

FIG. 4 is a bottom view of said toilet bowl chlorinator. It is understood that the design is bilaterally symmetrical. The water lines are shown broken away to indicate an indeterminate length.
